This invention relates to improvements in dolls and more specifically to jointed manikin dolls. The primary object of the invention resides in a movable joint for the arms, legs, or heads of dolls which will hold together regardless of expansion and contraction of the joined parts due to climatic conditions such as heat, cold, and moisture.

Manikin dolls have been constructed of wood-pulp, plaster, wax compositions, rubber compositions and other substances which contract and expand due to heat, cold, and moisture which effects the friction pin and socket arm, leg and/or head joints with which this type of doll is usually provided. Contraction of the jointed parts causes them to stick and likely to become broken if forcibly loosened, whereas expansion of the same effects a loosening of the joined parts and subsequent disconnection of the same. It is one of the main features of this invention to provide a pin and socket joint with compressible friction means for compensating for any contraction and expansion of the parts due to extreme changes in temperature and moisture.

Other features of the invention are to provide a friction joint for the jointed extremity members of dolls which permits the easy separation of the joined member for packing and shipping purposes; which enables the members to be moved to various fixed adjusted positions relative to the torso of the doll to effect different life-like poses; and which is simple and inexpensive of construction and manufacture.

Other novel features of the invention will become apparent as the following specification is read in conjunction with the accompanying drawing, in which:

Figure 1 is a front elevational view with parts broken away in section of the upper portion of a manikin doll in which the arms are connected to the torso by my improved friction joint.

Figure 2 is an enlarged detail vertical transverse sectional view on the line 2-2 of Figure 1, looking in the direction of the arrows.

Figure 3 is a fragmentary perspective view of the arm member removed from the torso.

Referring to the drawing by reference characters, the numeral 10 designates a doll of the manikin type which includes a solid torso body 11 having integral lower extremities or legs 12-12, and an integral head 13. The doll body 11 may be constructed of various materials such as molded wood pulp, rubber composition, plaster, or the like, and which materials are susceptible to expansion and contraction due to heat, cold and moisture. The opposite sides of the body 11 ad-

join the shoulders of the doll figure are flat and vertical and opening through these flat surfaces is a bore 14 of uniform diameter. The opposed ends of the bore 14 provide sockets for freely receiving pins 15 which extend from the upper ends of extremity members in the form of arms 16. The pin 15 of each arm member shown in Figure 1 is integral with the arm and is constructed of the same material as that of the arm, such material being the same as that mentioned hereinbefore as regards to torso body 11. However, the pin 15 may be in the form of a wooden dowel, as shown in Figure 4, and which will be more fully described hereinafter. Like the body 11, the pin 15 is also susceptible to expansion and contraction due to heat, cold and moisture, and should the pin be frictionally engaged directly with the walls of the bore 14 to hold the arm member 16 joined to the torso body 11, expansion of the parts 20 is likely to cause a cracking or breaking of the body and arm. Should the pin for instance contact relative to the walls of the bore 14, the arm 16 would become loosened and fall from its connection with the body 11. To compensate for 25 expansion and contraction of the parts while maintaining a tight friction fit therebetween, I provide an opening or bore 17 which extends transversely through the pin 15. Threaded through the opening 17 is a flexible compressible 30 friction element 18 which is of a length greater than the length of the opening 17 so that the terminal ends 19-19 extend from opposite ends of the opening. The friction element 18 may be in the form of a length of felt, fabric, shoe string, or the like, and in manufacture a long length of 35 the material may be threaded through a number of the openings in the arm member 16 and subsequently cut at the proper length to provide the terminal end portions 19-19 for each of the arm 40 members. In Figure 3 of the drawing it will be noted that normally the terminal ends 19-19 of the friction element 18 extend at right angle to the axis of the pin 15, but as the pin 15 is inserted into the end of the bore 14, the terminal 45 ends 19-19 will fold outwardly as shown in Figure 2 so as to tightly fit between the walls of the bore 14 and the peripheral surface of the pin 15. The terminal ends 19-19 of the friction element 18 are resilient to compensate for expansion and 50 contraction between the walls of the bore 14 and the pin 15 and to permit of the manual turning of the arm 16 to impart adjustable life-like poses of the manikin doll. Also, the friction joint permits of the removal of the arm 16 for packing 55 and shipping purposes.

UNITED STATES PATENT OFFICE

2,381,897

JOINTED MANIKIN DOLL

Max Geller, Brooklyn, N. Y.

Application September 22, 1942, Serial No. 459,233

1 Claim. (Cl. 46—173)

While I have shown and described what I consider to be the most practical embodiment of my invention, I wish it to be understood that such other modifications in construction and design as come within the scope of the appended claim may be resorted to if desired.

Having thus described the invention, what I claim as new and desire to secure by Letters Patent of the United States, is:

In a doll having a rigid body, said body having a pin receiving recess therein which is round in cross section, an extremity member, a pin car-

ried by and extending from said member, said pin extending into said recess free of the walls thereof, said pin having an opening extending transversely therethrough, and a flexible friction element passing through said opening and having its terminal end portions folded against opposed sides of the pin and in tight frictional contact with the side walls of said recess for turning and reattachably connecting the member to said body.

MAX GELLER.

CERTIFICATE OF CORRECTION.

Patent No. 2,381,897.

August 14, 1945.

MAX GELLER.

It is hereby certified that error appears in the printed specification of the above numbered patent requiring correction as follows: Page 1, first column, line 6, strike out the word "to" second occurrence; and second column, line 11, for "to torso" read --the torso--; line 21-22, for "contact" read --contract--; line 53, for "of the" read --to the--; page 2, second column, line 9, for "retachably" read --detachably--; and that the said Letters Patent should be read with this correction therein that the same may conform to the record of the case in the Patent Office.

Signed and sealed this 25th day of December, A. D. 1945.
